MACHINE FOR MAKING WRAPPERS

Michael J. Milmoe, Glen Ellyn, and Clarence J. Malhiot, Oak Park, Ill., assignors to F. B. Redington Co., Chicago, Ill., a corporation of Illinois

Application February 15, 1937, Serial No. 125,806

18 Claims. (Cl. 93—1)

This invention relates to an apparatus for making or forming wrappers in which articles may be wrapped.

An object of the invention is to provide a new and improved apparatus or feeding and cutting mechanism for feeding a strip of tape to a predetermined position with respect to a web of paper or wrapping material which is being fed, and applying the tape, which has been cut, to the material at such an angle as to cause the end of the tape to overlie the edge of the material a predetermined distance, whereby a finished wrapper with an opening tape, of the type disclosed in Patent No. 2,019,191 issued to Michael J. Milmoe is produced.

A further object of the invention is to provide a mechanism for feeding and cutting a strip of tape, for feeding a web of wrapping material and feeding the tape in proper timed relation with the material being fed, to properly bring the tape and the material to a predetermined position at a predetermined time.

A further object of the invention is to provide a mechanism which feeds and cuts a strip of tape, superposing the cut tape upon a sheet of wrapping material which has had a narrow portion of wax applied thereto for adhering the tape to the material to provide a laminated sheet or wrapper.

An additional object of the invention is to provide a method for producing a laminated material which consists of cutting a strip of tape and feeding it into a position for superposing it on a sheet of pre-waxed wrapping material for the purpose of adhering the tape thereto.

A further object of the invention is to provide a mechanism which includes means for cutting and then feeding a strip of tape to a predetermined position with respect to a sheet of paper being fed, which is provided with means for adhering the cut tape in superposed relation on the wrapping material and arranging the tape at such an angle to cause the end of the tape to overlie the edge of the paper to provide a tearing strip, and the provision of means for cutting the material at a point adjacent the end of the overlying strip of tape.

Numerous other objects and advantages will be apparent throughout the progress of the following specification.

The accompanying drawings illustrate a selected embodiment of the invention and the views therein are as follows:

Fig. 1 is a side elevation of the apparatus;

Fig. 2 is a top plan view thereof;

Fig. 3 is a detail plan view of some of the mechanism, showing the pusher arm positioning the tape to the paper or wrapping material;

Fig. 4 is a side elevation of the driving gears;

Fig. 5 is a top view of the waxing apparatus;

Fig. 6 is a detail elevational view of the tape cutters;

Fig. 7 is a diagrammatic view showing the angular position of the tape as applied to the paper;

Fig. 8 is a detail view of one of the superposing rolls showing the press strip on the roll;

Fig. 9 is a detail view showing the pusher arm positioning the tape against the guide member;

Fig. 9A is a detail view of the pusher on an enlarged scale and shows the tape guide co-operating with the said arm;

Fig. 10 is a detail sectional view of the lower superposing roll, showing the heating unit contained therein;

Fig. 11 is a detail elevational view showing some of the mechanism for operation of the upper superposing roll;

Fig. 12 is a front elevational view of the mechanism shown in Fig. 11;

Fig. 13 is a detail view of a cooler element or chiller pipe;

Fig. 14 is a detail view of the cooler or chiller pipe, showing its applications to the superposed material; and

Fig. 15 is a detail elevational view showing the manner in which the tape is fed to the wrapper to become adhered thereto.

Referring to the drawings, and more particularly to Figs. 1 and 2 thereof, 1 designates a suitable frame or supporting structure which has journaled at an upper portion thereof, in any conventional manner, a transverse shaft 2, upon which is mounted a guide roller 3. Paper, or other desirable wrapping material 4, is fed from a supply roll to and about the guide roller 3 into contact with a waxing roller 5. The wax roller 5 is fixed to a shaft 6, Fig. 5, which shaft 6 is journaled in bearings 7 and 8 of a frame 9 supporting the wax pot or bath 10. The frame 9, containing the wax pot 10, is attached to the main frame or support 1 of the apparatus by the bracket members 11 and 12, Figs. 1 and 5. At the bottom of the frame 9 there are recess 50 bearings 13 and 14, Fig. 1, which contain heating units 15 for heating the wax in the pot 10 to the proper temperature to keep the wax in melted condition.

The shaft 6, upon which is mounted the wax

55

roll 5, is immediately adjacent a shaft 16, Figs. 1 and 5, which latter shaft is adjustable with respect to the shaft 6. The shaft 16 is provided with a recessed portion 17 and is adapted to cooperate with the enlarged or platen portion 18 on the roll 5. The shaft 16 is adapted to be shifted in its bearings 19 so as to bring an edge 17a either closer or farther away from the platen portion 18 to increase or decrease the space between the platen portion whereby the amount of wax on the platen portion 18 can be determined. The space between the recess 17 and the high spot 18 therefore controls the thickness of the wax and this thickness is determined by the adjustability of the shaft 16.

A bracket arm 21 is fixed to the end of the shaft 16 and extends forwardly, as clearly indicated in Figs. 1 and 5. This bracket arm 21 has an opening in its outer end to the right, Fig. 1, through which a screw 22 extends. This screw 22 threadedly engages a block or boss 22a, Fig. 1, on a part of the main frame or supporting structure. A wing nut 23 threadedly engages the upper end of the screw 22 and determines the amount of adjustment given to the shaft 16, there being a spring 24 arranged between the under side of the bracket 21 and the upper side of the boss 22a. Therefore, by operating the wing nut 23, the bracket 21 will be moved and consequently turn the shaft 16 in its bearing 19 to bring an edge 17a of the recess closer or farther away from the enlarged or platen portion 18 on the wax roll 5. Adjustment, therefore, can be made to govern whatever thickness of wax may be desired. The purpose for the regulation of the amount of wax is to prevent too much wax upon the high spot 18 of the roller 5 from being applied to the material 4 which might subsequently spread over the remainder of the material.

The material or paper 4, which is being fed about the roller 3, Fig. 1, comes in contact with the platen 18 of the roller 5, which is rotating through the wax bath 10, and deposits on the paper or other wrapper material the proper amount of wax. The wax is disposed on the material 4 in an angular position equivalent to the formation of the platen 18, and is also of a substantially equivalent width, Fig. 5.

The paper 4 is further fed around tension guide rollers 25, 26 and 27, Fig. 1, which are rotatably mounted on shafts 28, 29, and 30 respectively. The shafts 28, 29 and 30 are rigidly mounted on the frame 1. The feed of the paper 4, with its waxed portions, continues from roll 27 into contact with the superposing or pressing rolls 31 and 32, Fig. 1, where it is adapted to receive a strip of tape.

A transverse stationary shaft 33, Figs. 1 and 2, which is located at the left of the apparatus, immediately to the left of the wax bath frame 9, is fixed to the main frame 1. The shaft 33 has mounted thereon a rotating tape supply roll 34, from which tape 35 is fed into the apparatus. Journalized to the frame 1 at 36 is an arm 31, Fig. 1, which acts as a friction arm for the tape supply roll 34 for supplying tension to the roll 34 to prevent unnecessary unrolling of the tape. The tape is fed from the roll 34 into guide members 38 which are disposed vertically in order to turn the tape over to a vertical position causing the tape to come off the spool at a proper angle at all times. To the left of the vertical guides 38 is an angularly disposed channel guide member 39, Figs. 1 and 2, which is rigidly secured

to the frame 1 by the bracket member 40. The channel guide receives the tape coming from the vertical guides 38 and turns the tape back to its flat horizontal position as it is being fed downwardly into the channel. The guide member 39 has a heating element 41 contained therein, which heats and irons out the tape as it passes through the channel guide member 39, in order to eliminate any wrinkles or creases which might be present.

At the lower end of the guide member 39 and immediately adjacent thereto is a horizontal guide channel 42 which is attached to the frame in any suitable manner, and receives the tape from the guide member 39, the tape moving past a guide pin 43. This guide pin 43 assists in guiding the tape into the channel 42. At the forward end of the channel 42 are feed rolls 44 and 45 which are mounted upon parallel shafts 46 and 47, respectively, Fig. 1. The shaft 47 is journaled to the frame by the bearing 48, which is integral with the extension 49 of the frame 1. The upper shaft 46 is the drive shaft, and has a drive gear 50, Fig. 2, contacting a lower gear (not shown) on the shaft 47. These latter gears cooperate to rotate the rolls 44 and 45 to feed the tape 35.

Immediately beyond the feed rolls 44 and 45, and substantially in the same parallel plane, is a pair of cutter rolls 51 and 52, Figs. 1 and 6, which is mounted on shafts 53 and 54, respectively. The shaft 54 is journaled at one side to the frame 1 by the bearing 55, and the shaft 53 is journaled by the bearing 56 which is integrally connected with the arm 57 and extends from the bearing 55 in the extension 58 of the frame 1, Figs. 1 and 3. The bearing 56, arm 57 and extension 58 are rigid parts of the frame 1. The shaft 54 is the actuating shaft and is connected by a universal coupling 59, Figs. 2 and 3, to the shaft 60 which is rotated by a gear 61, Fig. 2.

The upper cutter roll 51, Fig. 6, is driven by the lower roll 52 through conventional gear mechanism. The upper roll 51 is provided with a cutter knife 62 co-operating with a cutter knife 63 in the lower roll 52 to intermittently cut the tape off in predetermined lengths to provide tearing strips. The cutter rolls 51 and 52 are constantly rotated, and cut a piece of tape on every rotation, in synchronization with the feed of the tape.

Lying adjacent and immediately beyond the cutter rolls 51 and 52 is a channel guide 64 attached to the frame 1 by means of a bracket 65, Fig. 1.

Above the guide 64 and fixed to the frame, is a transverse extending bracket arm 67, Figs. 1 and 3. At one end of the bracket arm 67 is a vertical recess 68 which receives a vertical shaft 69. Around the shaft 69 and below the bracket arm 67 is a vertically disposed bearing 70 which has integrally connected thereto an angular pusher arm or bar 71. This arm is of angular configuration and extends horizontally to the side and beyond feed rolls 72 and 73.

A bearing 66 is integral with the arm 67 and carries a pivotally or swingingly mounted lever arm 74, Figs. 1 and 3. At the end of the extension arm 74 is a bearing 75, to which is journaled a rotatable shaft 76. The upper feed roll 73 is mounted on the shaft 76 while the lower feed roll 72 is mounted upon a rotatable shaft 77. The shaft 77 is journaled at one end to the bearing 78, Fig. 1, which bearing is integral with the extension 79 of the frame 1. The op-

posite end of the shaft 77 is journaled to the frame 1, and carries a gear (not shown) which co-operates with an upper gear 80, Fig. 3, to drive the upper shaft 76 and the feed roll 73. 5 The shaft 76 also carries a barrel cam which is rotated with the shaft 76, and this cam is adapted to co-operate with a roller 81, Fig. 2, which is mounted on the pusher bar 71. As the shaft 76 is rotated by the lower shaft 77, the cam 81 will be rotated to position the high spot of the barrel cam into engagement with the roller 81 on the pusher bar 71, causing the bar 71 to be pushed into contact with the tape 35, the tape being fed by the feed rolls 72 and 73, into and against a guide 82, Figs. 1, 2, 9 and 9A, to properly position the tape 35. A spring 83, Fig. 2, is attached at one end to the pusher arm and at the other end to the frame 1 and moves the arm back when the high spot of the cam is not contacting the roller 81. The guide 82 is disposed beyond the feed rolls 72 and 73 and is bracketed to the frame 1 by the bracket 84, Fig. 1. The barrel cam, in co-operating with the roller 81 of the pusher arm, can move the pusher arm 71 since this arm 71 is integral with the vertical bearing 70, which is rotatable on the vertical shaft 69.

The tape 35 moves forwardly to the right, Fig. 1, at an acute angular position with respect to an edge of the web of wrapping material 4 and at an angle with respect to the plane of the wrapping material. When the tape reaches the position shown at the point indicated at A, Fig. 2, the cut strip of tape will become adhesively attached to the wrapper 4 at which time it will lie in the plane of the wrapper 4 but at an acute angle with respect to the edge of the wrapper. The guide arm 71, which is controlled by a cam as previously mentioned, therefore guides the tape in its angular position until it is just about ready to be attached to the wrapper when the cam will cause the guide arm to swing backwards toward the top, as viewed in Fig. 2, to permit the new movement of the tape when it is attached to the wrapper. The pusher arm 71, therefore, pushes the tape into the guide 82 and holds the tape within the recess formed in the guide, Fig. 9A, until the tape is to be transferred to the wrapper at which time the cam will cause the pusher arm 71 to swing back slightly to permit the said transfer. However, after the transfer has been made the pusher arm 71 will move back again to the position shown in Fig. 9A and cause the tape 35 again to assume its angular position.

The guide 82 is provided with a cut-out portion, as indicated in Fig. 9A, into which the tape 35 is received as it is riding on the surface of the part of the frame or supporting member 1.

The guide members, and the feed rolls which feed and guide the tape 35, are so disposed with respect to the feeding position of the waxed material or paper 4, that the tape 35 is fed at an angular position to the paper, Figs. 2 and 3. The synchronizing of the feed of the tape 35 with that of the feed of the paper 4 brings a cut piece of tape into exact underlying position with the waxed portion of the paper as the tape and paper are engaged by the pressing rolls 31 and 32.

The superposing or pressing rolls 31 and 32 are adjacent the end of the channel guide 82 and the pusher arm or bar 71. The purpose of these rollers is to press a cut piece or strip of tape 35 into contact with the waxed portion of the paper 4, to cause the tape to be adhered to the paper 4, see Figs. 10, 11 and 12. The lower roll 31 is enlarged with respect to upper roll 32 and has a

transverse extension 85, Figs. 9 and 10, and a recessed or core portion 86 therein, Fig. 10. The core 86 is adapted to receive a rigid shaft 87 which has a hollow recess or portion 88, which contains a heating unit 89. The shaft 87 and the heating unit 89 are mounted in a stud bearing 90 which is integrally connected to the frame by a bracket 91, Fig. 1. The stud bearing 90 lies adjacent the lower roll 31 and bolts the shaft 87 to the frame, Fig. 10. The core member, which contains the shaft 87 and the heating unit 89, has the further purpose of decreasing the weight of the lower roller 31, and at the extreme end of the extension 85 there is provided a smaller recess 92 which is adapted to receive a shaft 93, the extension 85 and the roll 31 being driven by the shaft 93.

The lower roll 31, Figs. 8 to 10, has circumferentially enlarged portions or high spots 94 which act as platen pressers. These parts 94 are angularly disposed in such a manner that upon rotation they are brought into alignment with the angular position of the tape being fed and the angularly extending waxed portion on the paper 4. The heating unit 89, contained within the roll 31, is for the purpose of heating the waxed portion of the paper 4, which may have cooled off to some degree, and assists the wax in adhering the tape 35 to the paper 4.

The presser roller 32 is smaller in diameter than the roller 31, but operates in conjunction therewith, being positioned immediately above the roller 31. This roll 32 is fixed to a revolably mounted shaft 95, Figs. 1, 11 and 12, and is of an increased width relative to roll 31. The shaft 95 is journaled at 96 to a bracket 97, which is fastened to a boss or projection 98 on a boss or lug 99, Fig. 12. The member 99 surrounds a shaft 100, and is fixed thereto. The shaft 100 is freely or pivotally mounted in the angle bracket 101. The angle bracket 101 is rigidly attached to the frame 1 by means of a bolt 102. Securely attached to the bracket 97 is an angular scraper arm 103 which engages the upper roll 32 to remove any excessive wax therefrom. The gearing 99 is free to have oscillatory movement with the shaft 100. To the rear of the roll 32, and mounted on the shaft 95 is a cam 104 which rotates with the shaft 95. This cam 104 has enlarged circumferential portions, Figs. 11 and 12, which contact a cam plate 105. The cam plate 105 is rigidly secured to the extension of the arm 106 which is rigidly fastened to a rigid stud shaft 107 by means of a bolt 108, Fig. 11. The plate 105 on the extension 106 extends into a position to be contacted by the cam 104.

When the cam 104, Fig. 12, engages the plate 105 it will cause the shaft 100 to turn in its bearing in the bracket 101 and move the roller 32 from its normal operating position, as shown in dotted lines in Fig. 15, to the full line position shown in that figure, and the web 4 will be in the position shown in Fig. 15, providing sufficient clearance to permit a piece of cut tape 35 to be properly positioned. Therefore, as soon as the cam is off the member 105 the web 4 will be forced against the tape 35 and cause the tape to be adhered to the web.

A gear 109, Fig. 10, mounted upon the rotatable shaft 93 to rotate the roll 31, co-operates with a gear 110, Fig. 11, which is mounted on the end of the shaft 95 to rotate the cam 104 and the roll 32. Upon each rotation of the shaft 95 the high spots of the cam 104 are so positioned with respect to the high spot of the lower roll 31 to raise 75

the upper roll 32 slightly away from the roll 31. This clearance between the rolls 31 and 32 is of an amount substantially equal to the thickness of the tape and the waxed portion on the paper 5 4, and has the purpose of preventing too much pressure being applied by the pressure rolls 31 and 32, as too much pressure would cause the wax to be squeezed out from under the tape 35 onto the remainder of the paper. The arrangement provides the precise and predetermined application of pressure to properly adhere the tape 10 35 to the paper 4.

The swivel mounting of the roll 32 on the bracket 99 is to allow for a free oscillation to 15 provide the necessary spacing between the rolls. Also, the free oscillation of the roll 32 is such that it can be lifted up away from the roll 31 for cleaning purposes.

Beyond the superposing rolls 31 and 32 is a 20 cooler or chiller unit 119 which lies immediately above the laminated sheets. This chiller unit 119, Figs. 1, 13 and 14, may consist of a pipe 120 and elbow 121, attached to and extending through the frame. The pipe 120 has air vents 25 122 so disposed to immediately lie over the portion of the sheet where the tape was superposed thereto. These vents 122 blow a stream of cold air (from a unit not shown) upon the tape, the paper and the roll 32 to cause the wax to be 30 come chilled and consequently expedite adhesion between the strip of tape and the sheet.

The laminated sheet is picked up by feed rolls 125 and 126, Fig. 1, which are mounted on transverse shafts 127 and 128, respectively, supported 35 in the frame in any conventional manner. The roll 125 is mounted between pivoted arms to permit free vertical movement of this roll, while the lower roll 126 may be journaled in fixed bearings in the frame. A spring (not shown) is provided to urge the upper roll 125 into contacting engagement with the lower roll 126. A scraper arm 129 is fastened to the frame in any conventional manner to remove any excessive wax which may become lodged on the roller 126, Fig. 40 45 1. The tape 35 is fed downwards from the rolls 125 and 126 to the feed rolls 130 and 131 which are mounted on shafts 132 and 133, respectively, and then downwardly into a pair of rotary transverse cutters 134 and 135 which are mounted on 50 the rotatable shafts 136 and 137, Fig. 1. The cutters 134 and 135 are synchronized with the feed of the sheet to cut the laminated sheet transversely along a line 138, as clearly shown in Fig. 7. This line of cut 138 is immediately adjacent 55 the free end of the extending strip of tape which previously has been adhered to the sheet of paper. The shaft 133 may be a power shaft to drive the cutter roll 134 and its co-operating cutter roll 135.

60 The shaft 133, Fig. 4, may have a sprocket 139 attached thereto over which a sprocket chain 140 passes, the chain 140 being driven by any prime mover such as a motor (not shown). On the shaft 133, behind the sprocket 139, is a gear (not 65 shown) which engages an idler gear 141, Fig. 4, mounted on a shaft 142, which drives a gear 143 mounted on shaft 128 for the feed roll 126, Fig. 2. An idler gear 144 mounted on shaft 145 contacts the gear 143 and also contacts a gear (not shown) mounted behind the sprocket 146 on the shaft 93. The shaft 93 drives the presser roll 31 and the upper roll 32 through the gears 109 and 110, see Fig. 11. The sprocket 146 is connected to a sprocket chain 147 which is connected to a sprocket 147a, Fig. 4, for driving the 70 75

wax shaft 6 to rotate the wax roll 5. The gear (not shown) behind the sprocket 146, also engages an idler gear 148 which in turn drives the gear 61 mounted on the shaft 68 to drive the shaft 54 through the coupling 59 and the shaft 60, Fig. 2, for the tape cutter rolls 51 and 52. The shaft 54, Fig. 3, has a gear 150 to contact an idler gear 151 mounted on shaft 152, which also engages a gear 153 mounted on shaft 47 for driving the feed rolls 44 and 45, Fig. 1. The ratio of the 10 driving gears for feeding and cutting the tape, and for waxing and feeding the paper, and for the subsequent cutting of the laminated sheet is such that they are in synchronized relationship with each other for the purpose desired. 15

In operation, the tape 35 is fed from the supply roll 34 through the guide channels 39 and 42 to the feed rolls 44 and 45, where it is fed into the cutting rolls 51 and 52. The cutting rolls rotate to cut the tape into a predetermined strip or 20 length. The strip of tape is then fed through the guide channel 64 into the feed rolls 72 and 73, which feed the tape along a horizontal guide member 82 where a pusher arm, co-operating with the feed roll shaft 76, positions the tape 35 accurately against the guide 82. In this position the tape is ready to be fed into the pressing rolls into contact with the sheet 4.

The feeding of the tape up to this position has been at an angle with respect to the feed of the sheet 4. The sheet 4 is fed around a guide roll 3 into contact with a waxing roll 5 which deposits a portion of wax thereon. The sheet 4, with its waxed portion, is fed around the tension rolls into contact with the pressure rolls 31 and 32, 35 where it is to receive the pre-cut strip of tape. The rolls 31 and 32 engage the strip of tape and the pre-waxed web of paper to press the tape into engagement with the wax on the web. The tape 35 is accurately fed from an angular position to correspond to the angularly disposed waxed portion on the web 4. The presser rolls also feed the laminated sheet past a chilling unit 119 into the feed rolls 125 and 126, downwardly to contact the feed rolls 130 and 131, where they are 40 fed into the cutter rolls 134 and 135. The cutter rolls are rotated to cut the advancing sheet transversely on a line of cut 138 which is adjacent and in alignment with the free end of the extending strip of tape on the sheet. 45 50

Changes may be made in the formation, construction and arrangement of the parts without departing from the spirit of the invention or sacrificing any of its advantages, and the right is hereby reserved to make all such changes as 55 fairly fall within the scope of the following claims.

What is claimed as new and desired to be secured by Letters Patent is as follows:

1. A mechanism for forming wrappers having 60 tearing strips, comprising means for applying a hot wax along a line at a predetermined angle to a portion of a web of material, means for feeding the web, means for feeding a tape at an angle to the web being fed, means for cutting the tape 65 into predetermined lengths, means for feeding the cut tape on the web, said means including guide means for positioning the tape parallel to the waxed portions with the end of the tape extending beyond a side of the web, and means for pressing the tape into adhering relationship with the waxed portions on the web, with an end of the tape extending beyond the outer edge of the web. 70

2. A mechanism for forming a laminated material comprising means for feeding a strip of 75

material, means for cutting the strip, said feeding means being angularly disposed with respect to a moving web, said web having angularly disposed adhesive portions, said strip-feeding means causing the cut strip to travel at an angle relative to said moving web to position the strip onto the angled adhesive portions of the web, heated presser rolls for pressing the strip into adhering relation with the adhesive portion, one of 10 said presser rolls being vertically movable to limit the amount of pressure.

3. A mechanism for forming wrappers having tearing strips comprising means for feeding a sheet of wrapping material, means for feeding a strip of material, means for cutting the strip, said strip feeding means being angularly disposed with respect to the moving sheet, means for applying adhesive to the sheet along a line at an acute angle to an edge of the sheet, said strip-feeding means causing the cut strip to travel at an angle relative to the said moving sheet to position the strip in alinement with the adhesive on the sheet 15 presser rolls for pressing the strip into adhering relation with the sheet, one of said presser rolls having a circumferentially enlarged portion disposed at an angle to conform to the angulation of the adhesive and the strip.

4. The method of forming a package wrapper having a tearing strip which consists in applying an adhesive to a sheet of wrapping material at 30 an acute angle to an edge of the sheet, cutting a strip of tape, feeding the cut strip to the sheet at an angle to said edge of the sheet, superposing the sheet and cut tape with the tape parallel to the applied adhesive and with an end of the tape extending beyond an edge of the sheet, and pressing the tape and sheet into adhering relation.

5. A method of forming wrappers having tearing strips which consists in feeding a web of 40 wrapping material to a predetermined point, applying to the web during its movement to the predetermined point an adhesive coating along a line at an acute angle to an edge of the web, cutting a strip of tape, feeding the cut strip to the web at an angle to said edge of the web, superposing the cut tape and web with the tape parallel to the applied adhesive and with an end of the tape extending beyond the edge of the wrapper, pressing the tape and web into adhering relation, and cutting the web transversely at a 50 point opposite the extending end of the tape.

6. A mechanism for forming a laminated material comprising means for feeding a web of material, presser rolls into which said web is fed by said feeding means, one of said rolls being movable relatively toward and from another roll, means for applying adhesive to said web during its movement toward said presser rolls, means for successively feeding strips of material to said 60 presser rolls, and means operable in timed relation to said last mentioned feeding means to operate the movable presser roll to permit the superposing of the strip and web along the applied adhesive and for pressing said strip and web 65 into adhering relation.

7. A mechanism for forming a wrapper having a tearing strip, comprising means for feeding a sheet of wrapping material, presser rolls between which said sheet is fed by said feeding 70 means, means for feeding a strip of material, means for cutting the strip, means for guiding the cut strip between said presser rolls at an angle with respect to an edge of the moving sheet, means for applying adhesive to the sheet during 75 its movement to the presser rolls, said adhesive

being applied along a line at an acute angle to the edge of the sheet, and means operable in timed relationship to the cut strip feeding means to position the cut strip in said guiding means whereby the cut strip is alined in the presser rolls with the adhesive on the sheet of wrapping material and with an edge of the cut strip extending beyond an edge of the said sheet. 5

8. A mechanism for forming wrappers having tearing strips, comprising means for feeding a web of wrapping material, means for applying an adhesive to a portion of the web along a line extending at an angle to a side edge thereof, said means comprising an adhesive reservoir, a roller over which the web passes, said roller 15 having an enlarged portion extending circumferentially thereof at an angle to a side edge thereof and a shaft adjustably mounted relative to said roller for movement toward and away from the periphery thereof, said shaft having a recessed portion adapted to cooperate with the end portion of the roller to control the thickness of adhesive applied to the web by said enlarged portion, means for feeding cut strips of tape onto the web to angularly position it relative thereto 20 along the line of adhesive and with an end extending beyond the side edge of the web, and means for pressing the tape into adhering relationship with the adhesive portion of the web. 25

9. A mechanism for forming wrappers having tearing strips comprising means for feeding a web of wrapping material, means for feeding a strip of tape at an angle to a side edge of the web, means for positioning the tape and web in superposed, angular relation with the tape 30 extending beyond a side edge of the web to form a tearing tab and means for adhering the tape to the web in such angular relation and with the tape extending beyond the edge of the web. 35

10. A mechanism for forming wrappers having tearing strips, means for feeding a web of wrapping material, means for applying adhesive to a portion of the web along a line extending at an angle to said edge thereof, means for feeding a strip of tape to the web at an equal angle to the 40 said side edge of the web, said means including a guide for positioning the tape in juxtaposition to the web and parallel to the line of adhesive thereon with the end of the tape extending beyond the side edge of the web and means for 45 pressing the tape into adhering relation with the adhesive portion of the web with the end of the tape extending beyond the edge of the web. 50

11. A mechanism for forming wrappers having tearing strips comprising means for feeding a web of wrapping material, means for feeding a strip of tape at an angle to a side edge of the web, means for positioning the tape and web in superposed, angular relation with the tape 55 extending beyond a side edge of the web to form a tearing tab, means for adhering the tape to the web in such angular relation and with the tape extending beyond the edge of the web, and means for cutting the web transversely at a point substantially in alinement with the end of the 60 extended tape. 65

12. A mechanism for forming wrappers having tearing strips, comprising means for applying an adhesive along spaced parallel lines at a predetermined angle to a web of wrapping material, means for feeding the web, means for supplying a tearing tape, means for cutting the tape into pieces of predetermined length, means for feeding the pieces of cut tape in succession and at an angle to the web being fed, said means in- 70 75

- cluding guide means for successively positioning the pieces of cut tape parallel to the adhesive portions of the web with the end of each piece extending beyond an edge of the web, means for 5
pressing the pieces of cut tape into adhering relationship with the adhesive portions on the web, with an end of the tape extending beyond said edge of the web, and means for cutting the web transversely at a point beyond the portion of the 10
tape secured to the web.
- 10 13. The method of forming a package wrapper having a tearing strip which consists in applying an adhesive to a sheet of wrapping material at an angle to an edge of the sheet, feeding a 15
strip of tape to the sheet at a corresponding angle to said edge of the sheet, superposing the sheet and cut tape with the tape parallel to the applied adhesive and with an end of the tape extending beyond an edge of the sheet, and pressing the sheet into adhering relation.
- 15 14. A method of forming wrappers having tearing strips which consists in feeding a web of wrapping material to a predetermined point, applying to the web during its movement to the predetermined point an adhesive coating along a line at an angle to an edge of the web, feeding a strip of tape at an angle to said edge of the web, superposing the tape and web with the tape 20
parallel to the applied adhesive and with an end 25
of the tape extending beyond the edge of the web, pressing the tape and web into adhering relation, and cutting the web transversely at a point beyond the portion of the tape secured to the web.
- 20 15. A mechanism for forming a laminated material, comprising means for feeding a web of material, relatively shiftable elements between which said web is fed by said feeding means, means for applying adhesive to said web along a 25
line at an angle to an edge of the web and during its movement toward said elements, means 30
for feeding a strip of material to and between said elements at a corresponding angle to said edge of the web, and means operable in timed relation 35
to said last mentioned feeding means for relatively shifting said elements to permit the superposing of said strip and web along the applied adhesive and for pressing said strip and web into adhering relation.
- 30 16. A mechanism for forming a wrapper having a tearing strip, which comprises means for feeding a sheet of wrapping material with an 35
adhesively coated portion extending diagonally of the sheet, means for feeding a strip of tape, guide means for superposing the strip and sheet, including relatively shiftable elements, said sheet and strip being fed between said elements by said feeding means, and means operable in timed relation to the strip feeding means for relatively shifting the elements of said guide means to permit the superposing of the strip and sheet along the applied adhesive with an end of the 40
tape extending beyond an edge of the sheet and for subsequently pressing said strip and said sheet into adhering relation.
- 40 17. A mechanism for forming a wrapper having a tearing tape, means for feeding a sheet of wrapping material, means for feeding a strip of tape at an angle to an edge of the sheet of wrapping material, relatively shiftable guides over and between which said sheet and tape are fed by said feeding means, and means operatively 45
connected with one of said feeding means for controlling the relative shifting of said guides in timed relation to the feeding of said tape and said web to press the sheet and tape into adhering engagement when said tape and web have 50
been fed in superposed relation with an end of the tape fed beyond a side edge of the web.
- 45 18. A mechanism for forming a wrapper having a tearing tape, comprising means for feeding a sheet of wrapping material having a line of adhesive inclined to an edge of the web, means for feeding a strip of tape at an angle to said edge of the sheet, which angle of feed is substantially equal to the angle of inclination of said 55
line of adhesive, said sheet feeding means and said tape feeding means including rotary guides relatively shiftable transversely of the direction of feed of said sheet and said tape, one of said guides having a peripherally extending raised portion for facilitating the proper angular positioning of the tape relative to the sheet, means for synchronously driving said sheet feeding means and said tape feeding means, and means operatively connected to said driving means and to said guides for shifting said guides relatively 60
to press the tape into adhering engagement with the sheet when a predetermined portion of the tape has been fed beyond the side edge of the sheet.
